UNITED STATES PATENT OFFICE.

ROBERT RUTTER, OF BUTTE CITY, MONTANA TERRITORY.

TIRE-UPSETTING MACHINE.

SPECIFICATION forming part of Letters Patent No. 381,085, dated April 10, 1888.

Application filed August 15, 1887. Serial No. 246,977. (No model.)

To all whom it may concern:

Be it known that I, ROBERT RUTTER, of Butte City, in the county of Silver Bow and Territory of Montana, have invented a new and Improved Tire-Upsetter, of which the following is a full, clear, and exact description.

The invention relates to machines for upsetting or shrinking tires; and the object of the invention is to improve the construction of machines of this character, the especial objects being to relieve the strain on the pins that connect the gripping-cams to the stationary and sliding heads and to allow a greater play of the gripping-cams by having the operating-levers clear of the working parts.

The invention consists in the construction and combination of parts, as hereinafter described and claimed.

Reference is to be had to the accompanying drawings, forming a part of this specification, in which similar letters of reference indicate corresponding parts in all the figures.

Figure 1 is a side elevation of a tire-upsetter embodying my improvements, one member of the frame thereof being broken away. Fig. 2 is a section on the broken line $x x$ in Fig. 1. Figs. 3 and 4 are perspective views of the lever and link, respectively, for operating the sliding head.

30 The frame of the machine consists, preferably, of two parallel bars, $a a$, which are secured to a bench or table by means of the angle-irons b , carried by said bars. In practice there will preferably be four of these angle-irons, two at each side near the ends of bars $a a$. A stationary head, c , is bolted in or between the bars a by means of a bolt, d , which also holds two opposite angle-irons b to the said bars. The stationary head c is formed with an inclined, serrated, or corrugated seat, c' , on its upper face and with an upwardly-extending post or standard, c^2 , from the inner face of which standard projects a boss, c^3 . A toothed or corrugated cam, e , is formed with a recess, e' , to receive the boss c^3 , and the pin f passes through the said cam and boss and through the standard c^2 , projecting beyond said standard to receive a lever, g , by which the cam is operated to clamp 45 the tire against the seat c' of stationary head c . The boss c^3 , projecting into the cam e , forms a bushing for the pin f , and relieves the latter of much of the strain to which it would otherwise be subjected.

50 55 The sliding head h is formed with an in-

clined toothed seat, h' , standard h^2 , and a boss on said standard, and has secured to it a cam, i , and a lever, j , for operating said cam, all of the said parts being identical in construction and arrangement with those of the stationary head c .

In a recess near the bottom of the sliding head h is secured a link, k , by means of a pin or screw, l , and the outer end of the link is formed with an eye, k' , into which eye the eccentrically-bored head m' of operating-lever m fits, and the said link and lever are secured between the bars $a a$ by means of a bolt or pin, n . With this construction, by throwing the lever m the link k is moved forward or backward, sliding the movable head h , to upset or release the tire, as desired.

By forming the frame of the machine of the two parallel bars $a a$ a cheap construction is obtained practically indestructible.

By having the cam-operating levers g and j arranged on the outside of the machine great play is allowed, even to the extent of a full turn or rotation, and they can be operated with more convenience and effect than if they were arranged within the vertical plane of the other working parts.

Having thus fully described my invention, I claim as new and desire to secure by Letters Patent—

1. The combination, in a tire-upsetter and with the heads or seats for the tire formed with standards and with bosses projecting from said standards, of gripping-cams recessed to receive the said bosses, substantially as shown and described.

2. The separate parallel bars a , stationary and sliding heads $c h$, gripping-cams $e i$, and means, substantially as described, for operating said cams and sliding heads.

3. The combination, with the stationary heads $c h$ and means for operating the latter, and the gripping-cams $e i$, of the pins f , projecting on the outside of the machine, and operating-levers $g j$, substantially as shown and described.

4. The combination, with the machine-frame, of the heads $c h$, formed with standards $c^2 h^2$, and bosses projecting laterally from said standards, the gripping-cams $e i$, levers $g j$, and the link and cam-lever $k m$, substantially as shown and described.
